UNITED STATES PATENT OFFICE.

JOHN A. OLBON, OF PATERSON, NEW JERSEY.

DESIGN FOR A STEERING-POST LOCK.

59,564.

Specification for Design.

Patented Nov. 1, 1921.

Application filed October 14, 1919. Serial No. 330,613. Term of patent 3½ years.

To all whom it may concern:

Be it known that I, JOHN A. OLBON, a citizen of the United States, residing at Paterson, in the county of Passaic and State of New Jersey, have invented a new, original, and ornamental Design for a Steering-Post Lock, of which the following is a specification, reference being had to the accompanying drawing, forming part thereof.

The figure is a plan view of a steering post lock, showing my new design.

I claim:

The ornamental design for a steering post lock, as shown.

JOHN A. OLBON.
